UNITED STATES PATENT OFFICE.

RUDOLF BEHRENS, OF NEW YORK, N. Y.

AMUSEMENT AERIAL RAILWAY.

1,300,555.

Specification of Letters Patent. Patented Apr. 15, 1919.

Application filed November 28, 1917. Serial No. 204,377.

To all whom it may concern:

Be it known that I, RUDOLF BEHRENS, a citizen of the United States, residing at New York, in the county of New York and State 5 of New York, have invented certain new and useful Improvements in Amusement Aerial Railways; and I do hereby declare the following to be a full, clear, and exact description of the invention, such as will enable 10 others skilled in the art to which it appertains to make and use the same.

This invention relates to amusement rail ways of the aerial type, and the primary object of the invention is to provide a car 15 structure, for travel over an aerial track which is constructed of a cable supported by suitable type of supports for imitating the riding in a dirigible balloon.

More specifically, the object of this invention is to provide a car structure for use 20 upon an aerial cable railway, which includes a supporting structure having a car pivotally carried thereby, which car travels beneath the cable or track of the railway and 25 has a balloon or bag connected thereto and positioned above the railway.

A further object of the invention is to provide means for rocking the car which carries the passengers during the travel of 30 the car over the railway which means includes a crank shaft and a plurality of sprockets which are carried by the bag or balloon of the car structure and an arm which is connected to the crank of the crank 35 shaft and to the car for rocking the car during the rotation of the crank shaft.

With the foregoing and other objects in view, this invention consists in such novel features of construction, combination and 40 arrangement of parts as will be hereinafter more fully described, illustrated in the accompanying drawings and claimed.

In describing the invention in detail, reference will be had to the accompanying 45 drawings wherein like characters designate like and corresponding parts throughout the several views, and in which:

Figure 1 is a side elevation of the improved car structure having parts thereof 50 broken away.

Fig. 2 is an end view of the car structure, and

Fig. 3 is a fragmentary section through 55 the balloon showing the car rocking mechanism in edge elevation.

Referring more particularly to the draw-

ings, 1 designates the cable over which the car structure travels. The cable 1 is supported by suitable supporting structures as illustrated in Fig. 2 of the drawings, comprising a horizontal arm 2 having a bar 3 attached to the upper surface of the same and extending longitudinally of the cable short distances in each direction from the arm 2. The cross arm 2 is supported by a 60 suitable standard 4 which is preferably constructed of angle iron or any analogous material and by varying the lengths of the various supports the elevation of the cable 1 may be varied to impart thrills to the persons riding in the cars traveling thereover. The track over which the car travels may be of any shape desired so as to provide either a straight or sinuous route for the cars traveling thereover, this track being of the well 70 known spiral type so as to cause the car to travel by gravity from a higher to a lower level, suitable elevating means being provided for returning the car to its initial starting point. 80

The car structure comprises a frame 6 which is substantially stirrup shaped and carries a tonneau 7 which is pivotally connected as shown at 8 to the bottom 9 of the stirrup-like frame 6. The pivot 8 of the tonneau 85 7 is positioned intermediate of its ends so as to allow a rocking of the same during the travel of the car over the track. The frame 6 has a shaft 10 supported thereby and extending rearwardly from the rear end of the 90 same upon which shaft is mounted a propeller 11. The propeller 11 is mounted for free rotation on the shaft 10 so that it will be rotated by the air current generated by the travel of the car, for the purpose of adding realism to the travel of the car and making it appear as if the car were being propelled by the propeller 11. 95

Brackets 12 are swivelly connected as shown at 13 at each end of the frame 6 to 100 the upper surface of the frame and these brackets have upstanding arms 14 formed thereupon, which arms are connected to the longitudinal braces 15 which extend centrally through the balloon or bag 16 of the 105 car structure. The balloon or bag structure 16 is shaped like the gas bag of an ordinary dirigible balloon and it travels above the cable 1 as clearly shown in the drawings.

The brackets 12 have rollers 17 rotatably 110 carried thereby, which rollers are provided with concaved peripheries for engaging and

riding upon the cable 1. The sides 18 of the brackets 12 include pivoted sections 19 which are provided so that when the car structure reaches one of the cross arms 2 the pivoted section will move upwardly to allow the car to pass the cross arm without interruption to its travel.

The roller 17 which is carried by the rear bracket 12 has a sprocket 20 attached thereto about which a sprocket chain 21 travels. The chain 21 also travels about a relatively large sprocket 22 which is mounted upon a shaft 23. The shaft 23 is rotatably positioned within the body of the balloon 16 and it is supported by the arm 14 and a bracket structure 24. A relatively small sprocket 25 is also mounted upon the shaft 23 and a sprocket chain 26 travels about this sprocket and about a large sprocket 27 mounted upon a shaft 28. The shaft 28 is supported within the balloon 16 directly above the forward end of the car structure and it is rotated by the rotation of the rollers 17 carried at the rear end of the car structure through the medium of the sprocket chains 21 and 26 and the sprockets 22, 25 and 27.

The shaft 28 has a crank arm 29 formed thereupon upon which is formed a wrist pin 30. A lever 31 is pivotally connected as shown at 32 to a brace 33 and it is provided with a longitudinally extending slot 34 formed therein which rides upon the wrist pin 30. A downwardly extending arm 35 is formed upon the arm 31 and it has a weight 36 formed upon or attached to its lower end. The arm 35 and the weight 36 act as a counter balance pendulum for the operation of the bar 31. A rod 37 is connected to the bar 31 and to the forward end of the tonneau 7 so that the movement of the arm 31 caused by the rotation of the shaft 28 will rock the tonneau 7 upon its pivot 8 for further adding to the thrills of the person riding in the tonneau.

The tonneau 7 may be constructed on any desired or practical plan having seats 40 positioned therein for holding the pleasure seekers riding within the car.

From the foregoing description taken in connection with the accompanying drawings the advantages of construction and the method of operation of the improved amusement aerial railway will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

1. In a pleasure aerial railway, the combination with a cable forming a track, of a car structure including a supporting frame work, a tonneau pivotally carried by said frame work and positioned beneath said cable, a balloon carried by said frame work and positioned above said cable, means for rocking said tonneau during the travel of the car structure, and rollers carried by said frame work and engaging said cable. 70

2. In a pleasure aerial railway, the combination with a cable forming a track, of a car structure for travel over said track including a frame work, a tonneau pivotally carried by said frame work, a balloon carried by said frame work, a plurality of guiding rollers carried by said frame work and engaging said cable, and means actuated by the rotation of one of said guiding rollers for rocking said tonneau during the travel 85 of said car.

3. In a pleasure aerial railway, the combination with a cable forming a track, of a car structure for travel over said track including a frame work, a tonneau pivotally carried by the lower portion of said frame work, a balloon carried by the upper portion of said frame work and positioned above said cable, rollers carried by said frame work and engaging said cable for guiding 95 the travel of said car structure, a pivoted arm positioned within said balloon, means operated by the operation of one of said guiding rollers for rocking said pivoted arm, and means connecting said arm and said tonneau for rocking the tonneau during the rocking movement of said arm. 100

4. In a pleasure aerial railway, the combination with a cable forming a track, of a car structure for travel over said track including a frame work, a tonneau pivotally carried by the lower portion of said frame work, a balloon carried by the upper portion of said frame work and positioned above said cable, rollers carried by said frame work and engaging said cable for guiding the travel of said car structure, a pivoted arm positioned within said balloon, means operated by the operation of one of said guiding rollers for rocking said pivoted arm, and means connecting said arm and said tonneau for rocking the tonneau during the rocking movement of said arm, and a counter balancing pendulum connected to said arm. 115

5. In a pleasure aerial railway, the combination with a cable forming a track, of a car structure for travel over said track including a frame work, a tonneau pivotally carried by the lower portion of said frame work, a balloon carried by the upper portion of said frame work and positioned above said cable, rollers carried by said frame work and engaging said cable for guiding the

travel of said car structure, a pivoted arm positioned within said balloon, means operated by the operation of one of said guiding rollers for rocking said pivoted arm, and 5 means connecting said arm and said tonneau for rocking the tonneau during the rocking movement of said arm, and a counter-balancing pendulum connected to said arm, and a propeller rotatably supported rearwardly

of the rear end of said car structure for idle 10 rotation during the travel of the car structure.

In testimony whereof I affix my signature in presence of two witnesses.

RUDOLF BEHRENS.
